ATTY.

UNITED STATES PATENT OFFICE.

JOHN HAROLD HAY, OF CALGARY, ALBERTA, CANADA.

VALVE, TAP, AND THE LIKE.

1,378,030.

Specification of Letters Patent. Patented May 17, 1921.

Application filed November 9, 1920. Serial No. 422,892.

To all whom it may concern:

Be it known that I, JOHN H. HAY, of the city of Calgary, in the Province of Alberta, Canada, a subject of the King of Great Britain, have invented certain new and useful Improvements in Valves, Taps, and the like, of which the following is a specification.

This invention relates to improvements in taps, valves, cocks and the like using a resilient ball as the valve member, and my object is to devise a construction in which the valve member, while entirely free, will be certain to properly seat on its seat, in which the valve member will be subjected to a minimum amount of wear, and in which the valve member may be quickly replaced with a minimum of inconvenience.

I attain my object by means of the constructions hereinafter described and illustrated in the accompanying drawing, which is a cross section of a water tap constructed in accordance with my invention.

1 is the casing of the tap provided with the usual inlet opening 2 and outlet nozzle 3. The casing is open at its upper end, which opening is closed by a screw cap 4. Through this cap extends the spindle 5, provided with the usual handle 6. The upper portion of the inside of the casing is threaded to receive threads formed on the enlargement 7 of the spindle.

Extending from one side of the casing above the inlet 2 to the lower side of the outlet 3 at the other side of the casing is the partition 8. This partition has an opening formed therein through which a depending portion 9 formed on the lower end of the spindle is adapted to pass. This depending portion 9 has a valve displacer 10 secured to its lower end in such a manner that the displacer is free to rock slightly in all directions.

11 is the valve member, preferably formed of rubber or other resilient material, which will be located in the casing below the partition 8. To enable the valve member to be easily placed in position, I form an opening in the lower end of the casing, which opening is closed by a screw plug 12. From the drawing it will be seen that the portion of the casing below the partition 8 is approximately spherical and that the end of the plug is dished out to follow the general shape of the sphere. The threaded portion

of the plug 12 has a plurality of notches 13 formed therein.

Suitable washers will be provided within the cap 4 and for the plug 12.

The spherical shaping of the portion of the tap below the partition 8 is very important, as there are no corners in which the valve member may lodge to prevent its proper seating to close the opening in the partition, and further there are no sharp edges to damage the valve member.

The valve member, it will be noted, is free to revolve in any direction, and thus any wear will be distributed over its entire surface, thus avoiding wear in spots.

The object of the notches 13 is to give the water a better opportunity of getting below the valve member to force it up against its seat on the lower side of the partition 8.

As the valve seat is on the lower side of the partition 8, it will be seen that the spindle 5 has to be operated in the reverse direction to the ordinary tap to open and close the tap, that is, the spindle will be screwed down to force the valve member from its seat, and up to allow the valve member to return to its seat.

Should it become necessary at any time to replace the valve member, it is merely necessary to remove the plug 12, when the valve member will fall out. To insert the new valve member, it is placed in the dished end of the plug and the plug then screwed into position.

From the above description, it will be seen that I have devised a construction which will satisfactorily attain the objects of my invention as set forth in the preamble of this specification.

While the invention is shown and described as applied to a water tap, it will be understood, of course, that the invention is also applicable to taps of other kinds and valves, cocks, and faucets of various kinds.

What I claim as my invention is:—

In a valve, the combination of a casing having inlet and outlet connections extending from its sides and an opening in its lower end; a partition dividing the casing into upper and lower chambers and extending from the upper side of the inlet connection to the lower side of the outlet connection, said partition having a passage formed therein having a valve seat on the under

side said lower chamber being substantially spherical; a resilient ball valve member loose in the lower chamber adapted to be seated against said seat; and a spindle operating in the upper portion of the casing having its lower end adapted to pass through the passage in said partition to force the valve member from its seat, said lower end having a valve displacer secured thereto and adapted to rock thereon, said displacer

having a flat lower surface; and a dished plug closing the opening in the lower end of the lower chamber, said dished plug having a plurality of notches formed in its edge.

Signed at Calgary this twenty-fifth day 15 of October, 1920.

JOHN HAROLD HAY.

In the presence of—

ELsie S. Whyte,
Hugh Melvin.
